UNITED STATES PATENT OFFICE.

WILLIAM REIFERSCHEID, OF CHICAGO, ILLINOIS.

PROPELLER.

1,286,105.

Specification of Letters Patent. Patented Nov. 26, 1918.

Application filed December 18, 1917. Serial No. 207,666.

To all whom it may concern:

Be it known that I, WILLIAM REIFERSCHEID, a citizen of the United States, and a resident of Chicago, in the county of 5 Cook and State of Illinois, have invented a certain new and useful Improvement in Propellers, of which the following is a description, reference being had to the accompanying drawing, which forms a part of my 10 specification.

My invention relates to a propeller for displacing air, being more especially adapted for use in connection with air craft; and has for its object the provision of a 15 propeller which is built entirely of thin sheet metal, but which will be durable and possess the necessary strength.

The invention contemplates a construction provided with a multiple of blades 20 which are secured at their inner ends to a suitable disk or flange secured to the hub, while the outer ends of the respective blades are fastened by suitable brace-members, some of which are secured to a circumferential reinforcing frame, while others are 25 directly connected to the hub; the respective blades being formed of a continuous sheet of metal curved substantially into "wing shape"; the blades being given a double 30 curvature, namely a suitable curvature from the inner to the outer end of the blade and a curvature from the forward or "cutting" edge to the rear edge; the curvature being of a pitch which will provide great pulling or displacing power.

The advantages of my improved construction will be more fully comprehended from the detailed description of the drawing, wherein:—

40 Figure 1 is a plan view of what may be termed the forward side of my improved propeller.

Fig. 2 is a side elevation thereof.

In the particular exemplification of the 45 invention, the propeller comprises a central portion in the nature of a disk or stay-plate 10 which may be secured to a shaft or constitute a flange formed integral with a hub-portion 11, see Fig. 2, adapted to receive 50 and be secured to the shaft 12, whereby power to the propeller is imparted.

I propose forming my improved propeller of thin sheet metal, with each blade 13 formed from a continuous sheet and given 55 a predetermined curvature or pitch which will offer the greatest resistance to the air

and therefore will increase the pulling power of the propeller.

In the drawing, I have shown a propeller having five blades, although it is apparent 60 that the number of blades may be increased or diminished according to the use for which the propeller is intended.

Each blade 13 is made arcuate or curved from end to end, as more clearly shown in 65 Fig. 2; that is, the blades are formed to describe the arc of a circle disposed radially from the center member 10, and therefore at right angles to the axis of the propeller, with the outer end of the forward portion 70 or "cutting" edge 14 of the blade disposed, substantially, in the same plane as the inner "cutting" or forward edge of the blade. The outer end of the blade at its forward or "cutting" edge is provided with a brace 75 member 15 disposed perpendicular to the outer end of the blade, that is, substantially at right angles to the horizontal plane occupied by the ends of the blade. The opposite end of the brace member 15 is suitably secured to a circumferential frame-member or ring 16. The member 16 is of a diameter similar to that of the circle described by the blades; the member 16 being arranged in spaced relation with the blades; 80 member 16 being at a distance from the plane occupied by disk 10 or inner ends of the blades, substantially equal to or slightly greater than the degree of rearward curvature of the blades, as clearly shown in 85 Fig. 2.

The transverse dimension or width of the respective blades increases from the inner ends toward the outer ends thereof, see Fig. 1; and the inner ends are preferably formed 95 or provided with an angular portion or flange 17 disposed in the direction of the face or convexed side of the blades; the flanges being also secured to the disk 10. The angularly disposed portions or flanges 100 17 increase in width from the front end toward the rear end of the blade, by reason of the downward curvature of the blades.

The curvature of the blades, both transversely and lengthwise of the blades, provides what may be termed a wing shape construction, wherein the rear edge 18 of each blade is disposed in a plane considerably removed from the plane of the forward or "cutting" edge of the blade; in other 110 words, with the propeller in the position illustrated in Fig. 2, the rearward edge 18

2
of each blade 13 is disposed in a horizontal plane considerably beneath the horizontal plane occupied by the forward or "cutting" edge 14 of the blade. It is clearly evident 5 with the construction shown and described, that the propeller will exert a great pulling force when revolved at proper speed in the right direction; the pulling force being exerted in the direction of the curvature or 10 convexity of the blades.

In the specific illustration of the invention, the increased transverse dimensions of each blade toward the outer end and the rearward curvature thereof is such that the 15 rearward outer end of the blade will be spaced from the forward "cutting" edge of the succeeding blade, a distance substantially four times the distance that the rearward inner end of the blade is removed from 20 the forward "cutting" edge at the end of the succeeding blade.

The rearward outer end of each blade is secured to the circumferential frame member or ring 16 by means of a suitable brace 25 or tie-member 19, see Fig. 2. The circumferential frame-member 16 is preferably shown provided with a circumferential flange portion 20, disposed toward the blades, which provides an additional brace 30 and reinforcement for the ends of the brace members 15 and 19.

The circumferential frame-member 16, in turn, is provided with radially disposed 35 braces or spokes 21, preferably spaced equi-distances apart, with their inner ends secured to the disk or flange portion 22 which may be secured to the shaft or to the hub-member 23. The outer, forward or "cutting" edge of each blade is also provided with a 40 diagonally disposed brace member 24, the opposite end whereof is properly secured to the flange 22.

The hub-portions 11 and 23 may be made 45 integral and thus assist in maintaining the proper spaced relation between the inner ends of the blades and disk 10 and the inner ends of the members or spokes 21 and disk 22; or the hub-portions 11 and 23 may be as 50 shown in Fig. 2 and so secured to the shaft-portion 12 as to prevent any movement lengthwise of the shaft. With the construction shown and described, a very rigid propeller is provided adapted to withstand the 55 strains to which it is subjected in the rapid revolution thereof; the propeller being adapted for use either in connection with air craft or for displacing air in air ducts and the like.

I have shown and described what I believe to be the simplest and best form of my invention, but the same may be modified in certain respects without, however, departing from the spirit of the invention.

What I claim is:—

65 1. A propeller, comprising a center plate

having a hub or shaft-engaging portion, a plurality of blades secured at their inner ends to said plate and radiating therefrom, the blades being curved in lengthwise and transverse directions, with the rear edges 70 of the blades disposed in a different plane from that occupied by the forward edges, a circumferential frame-member arranged in spaced relation with the outer ends of the blades, and brace-members intermediate of 75 the outer ends of the blades and said circumferential frame-members.

2. A propeller, comprising a hub portion, a plurality of blades secured at their inner ends to said hub-portion and curved in 80 lengthwise and transverse directions, with the inner and outer ends of the blades disposed in the same plane while the rear edges are disposed in a different plane from that occupied by the forward edges of the blades, 85 a circumferential frame-member arranged in spaced relation with the outer ends of the blades, said frame member being of substantially the same diameter as the diameter of the circle described by the blades, and brace members intermediate of the outer ends of the blades and said circumferential frame member.

3. A propeller, comprising a hub-portion, a plurality of thin sheet metal blades curved 95 so as to describe the arcs of two circles disposed at right angles to each other, the blades being of gradually increasing width from their inner to their outer ends, an elongated hub, means intermediate of the 100 inner ends of the blade and one end of the hub for securing the blades in place, a circumferential frame member, means whereby said frame member is supported from the opposite end of said elongated hub, and 105 brace members intermediate of the outer ends of the blades and said circumferential frame member.

4. A propeller, comprising an elongated hub-portion provided with a circumferential 110 flange at each end thereof, a plurality of blades curved in transverse and lengthwise directions, the inner and outer ends of the blades being disposed in substantially the same plane while the rear edge of each blade 115 is disposed in a different plane from that occupied by the forward cutting edge of each blade, the inner ends of each blade being secured to one of said circumferential flanges on the hub-portion, a circumferential 120 frame member, radially disposed means for securing said circumferential frame member to the flange at the opposite end of said hub, and brace members intermediate of the outer ends of the blades and said circumferential 125 frame member.

5. A propeller, comprising a hub-portion, a plurality of thin sheet metal blades curved in directions lengthwise and transversely of the blades, the inner ends of the blades be- 130

- ing secured to one end of the hub-portion, each blade being of increasing width from the inner toward the outer end thereof, with the rear edge of the blade disposed in a plane 5 considerably removed from the plane occupied by the forward or cutting edge of each blade, and means intermediate of the outer end of each blade and the opposite end of said hub-portion whereby the blades 10 are reinforced.
6. A propeller, comprising a hub-portion, a plurality of thin sheet metal blades curved in lengthwise and transverse directions, the blades being of gradually increasing width 15 from the inner toward the outer ends thereof, with the rear edge of each blade disposed into a plane beneath that occupied by the forward or cutting edge of each 20 blade, a circumferential frame member of a diameter substantially equal to the diameter of the circle described by the blades, brace members intermediate of said circumferential frame member and one end of the hub-portion, brace members intermediate of the outer ends of the blades and said circumferential frame-member, and diagonally disposed brace members intermediate of the outer ends of the blades and one end of said 25 hub-portion.
7. A propeller, comprising a hub-portion, a plurality of blades curved in lengthwise and transverse directions, the inner ends of the blades being secured to one end of the hub-portion, a circumferential reinforcing 30 member of diameter substantially equal to the diameter of the circle described by the blades, said circumferential member being secured to the opposite end of said hub-portion.
8. A propeller, comprising a plurality of thin sheet metal blades, each curved in lengthwise and transverse directions and of gradually increasing width from the inner toward the outer ends thereof, a circumferential frame-member of diameter substantially equal to the diameter of the circle 40 described by the blades, and brace-members secured to the circumferential frame-member and to the outer ends of the blades.
9. A propeller, comprising a hub-portion, a plurality of blades curved in lengthwise and transverse directions and of increasing width from the inner toward the outer ends thereof, and brace members intermediate of the outer ends of the blades and said hub-portion.
10. A propeller, comprising a plurality of blades secured at their inner ends to a common axis or hub, the blades being of gradually increasing width from the inner ends toward the outer ends thereof, the blades being curved in lengthwise and transverse directions, the forward cutting edges of all the blades being disposed in the same plane, the transverse curvature of each blade being such that the rear edge of each blade is disposed in a plane considerably removed from that occupied by the forward edge of the blade.

WILLIAM REIFERSCHEID.
